UNITED STATES PATENT OFFICE.

JOHN O. SCHROEDTER AND JOHN KELLING, OF MILWAUKEE, WISCONSIN, ASSIGNEES
TO MONARCH FLESHING MACHINE COMPANY, OF MILWAUKEE, WISCONSIN.

FLESHING-MACHINE.

1,382,126.

Specification of Letters Patent. Patented June 21, 1921.

Application filed February 24, 1920. Serial No. 360,616.

To all whom it may concern:

Be it known that we, JOHN O. SCHROEDTER, a citizen of the German Republic, and JOHN KELLING, citizen of the United States, and residents of Milwaukee, in the county of Milwaukee and State of Wisconsin, have invented certain new and useful Improvements in Flesching-Machines; and we do hereby declare that the following is a full, clear, and 10 exact description thereof.

Our invention pertains to improvements in flesching machines of that type illustrated in Patent No. 1,235,697, granted August 7, 1917.

15 As pointed out in that patent, machines of this character are designed to remove flesh from the inside of raw skins and furs, or to reduce the thickness thereof. In view of the fact that it is extremely difficult, except for experienced work-men, to properly dress skins with an ordinary flesching machine, adjustable guards are provided to render the machine more efficient and to permit the same to be operated by the average 20 work-man. The principal object of the invention is to provide a means for adjusting these guards in a much simpler manner than that used in the machine shown in said patent.

25 30 An additional object of the invention is to provide a simply constructed and efficient arrangement for detachably journaling the flesching knife in the supporting frame of the machine.

35 40 A still further object of the invention is to provide an adjustable protecting plate which, while normally in position partially encircling the flesching knife, can be swung to one side so as to allow the knife to be removed from its bearings.

45 With these and other objects in view the invention resides in the novel features of construction, combination and arrangement of parts which will be hereinafter more particularly described and claimed as shown in the drawings wherein:

Figure 1 represents a side elevational view of a portion of a flesching machine constructed in accordance with our invention.

50 Fig. 2 is a plan view of the parts shown in Fig. 1, the protecting plate being in section.

Fig. 3 is a front elevational view, partly in section, of the invention.

55 Fig. 4 is a detail sectional view taken sub-

stantially on the plane of the line 4-4 of Fig. 5.

Fig. 5 is a similar view on the plane of the line 5-5 of Fig. 4.

Fig. 6 is a view similar to Fig. 4, the axle retaining nut having been removed so as to show the axle in section.

Our improved machine is designed to be mounted upon a suitable supporting frame, the upper portion 1 of which is shown in 65 the drawings and has a pair of spaced vertical bearing standards 2 between which a rotary circular flesching knife 3 is adapted to be revolved by any suitable mechanism. In the present instance the means supporting the knife 3 carries a belt pulley 4 which is adapted to receive a suitable driving belt. However, it is to be understood that various other arrangements may be used for mounting the flesching knife, such as by the means 70 shown in Fig. 1 of the patent above referred to. Furthermore various changes may be made in other parts of the invention without departing from the principle thereof or sacrificing any of the advantages. 80

Each of the standards 2 is provided with a bearing 5 having a slot 6 opening therewith from one side so that an axle 7, on which the knife 3 is journaled may be readily disposed therein. By such an arrangement the flesching knife 3 may be always disposed in assembled relation with respect to the axle 7, while at the same time it may be quickly and easily removed from between the spaced rigid standards 2. 90

As may be readily seen from Figs. 4, 5 and 6, the outer face of each of the standards 2 is provided with an annular ridge 8 surrounding the opening forming the bearing 5, thus providing a socket 9. The portions of the axle 7 that project beyond the standards 2 are screw threaded and receive nuts 10, each of which has an annular flange 11 adapted to seat in the socket 9. When the nuts 10 are in coöperation with the 100 sockets 9, the axle 7 is effectively locked within its bearings. 95

In dressing a skin on the flesching knife 3, the workman stands behind the machine and back of an arcuate protector plate 12, which, 105 when in protecting position extends from approximately the top center of the knife 3 to the standards 2, and is approximately of a width equal to the distance between the latter. The lower end of this plate 12 has 110

2
a laterally extending attaching portion 13 which is vertically slidable between spaced lugs 14 formed on a carrying plate 15. The attaching end 13 is vertically slotted as at 16 to receive a clamp bolt 17 projecting from the carrying plate 15. By means of this bolt 17 the protector plate 12 may be vertically raised or lowered so as to dispose it substantially concentric with the fleshing knife 3.

10 One end of the carrying plate 15 has a pair of hinge knuckles 18 which are disposed on opposite sides of similar knuckle 19 carried by one of the frame bars of the supporting frame 1, these knuckles being hinged together by means of a pintle 20. The opposite end of the carrying plate 15 has a pair of ears 21 between which a securing bolt 22 may be swung to lock the carrying plate to the supporting frame so that the 15 protector plate 12 will be in operative position with respect to the fleshing knife. The bolt 22 being hinged to the frame 1 and having a wing nut 23 provides a quickly detachable locking means, although it is 20 obvious that another similar arrangement 25 would serve the same purpose.

When the carrying plate 15 is locked as shown in several figures of the drawings, that is to say when the protective plate partially encircles the fleshing knife and prevents the workman from leaning thereagainst and being injured by its edge, it is impossible to disconnect the fleshing knife since the openings 6 into the bearings 5 are toward the 30 said protective plate 12. Therefore in order that the fleshing knife may be taken from between the standards 2, the protective plate 35 12 is hinged as above described.

40 The portion of the fleshing knife on the opposite side of the standards from the protective plate 12 is provided with a pair of adjustable guards 24, one of which is disposed on each side of the knife and are shaped to conform to the peripheral edge 45 thereof. As in the patent above referred to, these guards 24 are designed to aid the workman in more effectively dressing the skin or hide by means of the knife 3, such 50 guards being adjusted for different types of skins and various operating conditions.

55 The improved arrangement for adjustably supporting the guards 24 is clearly shown in the accompanying drawings and since the structure used for holding each of the guards is the same, that on one side of the fleshing knife will alone be described. The guard 24 is provided with an ear 25 pivoted as at 26 to a head 27, the latter being formed on one end of a stem 28 and having 60 an arcuate slot 29 which receives a set screw 30 extending from said ear 25. This set screw 30 obviously secures the guard 24 in different adjusted positions with respect to the head 27. The stem 28 is slideable and rotatable in a bearing 31 carried by the upper

or free end of a lever arm 32, the lower end of the latter being pivoted as at 33 to one of the standards 2. The intermediate portion of the lever arm 32 has a slot 34 receiving the shank of a set screw 35.

70 The bearing 31, and consequently the guard 24, is movable toward and away from the fleshing knife 3 as a result of the pivotal action of the lever arm 32 and is held in different positions by said set screw 35.

75 We claim:

1. The combination with a fleshing machine having a fleshing knife, of a guard plate to be disposed adjacent to said knife, a lever arm pivoted to the machine to have 80 one portion swing toward and away from the plane of the knife, and means connecting the guard plate with the lever arm.

2. The combination with a fleshing machine having a fleshing knife, of a guard 85 plate to be disposed adjacent said knife, a lever arm pivoted at one end to the machine to permit the other end to swing toward and away from the plane of the knife, means connecting the guard plate with the last 90 mentioned end of the arm, and means intermediate the ends of the arm for securing the guard plate varying distances from the knife.

3. The combination with a fleshing machine having a fleshing knife, of a guard 95 plate to be disposed adjacent said knife, a lever arm pivoted at one end to the machine to permit the other end to swing toward and away from the plane of the knife, a stem extending from the guard plate and slidably mounted in the last mentioned end of the arm, and means for securing the arm to the machine to hold the guard plate varying 100 distances from the knife.

105 4. The combination with a fleshing machine having a fleshing knife, of a guard plate to be disposed adjacent said knife, a lever arm pivoted at one end to the machine to permit the other end to swing toward and away from the plane of the knife, a stem extending from the guard plate and slidably and rotatably mounted in the last 110 mentioned end of the arm, and means for securing the arm to the machine to hold the guard plate varying distances from the knife.

115 5. The combination with a fleshing machine having a fleshing knife, of a guard plate to be disposed adjacent said knife, an 120 arm secured to the machine, a stem extending from the arm and having a head, said guard plate being pivoted to the head, the head having a slot, and a screw extending from the guard plate through the slot to adjustably clamp the latter to the head of the stem.

125 6. In a fleshing machine, a supporting frame, one portion of the frame having a bearing, an axle receiving slot providing 130

an entrance to the bearing, a rotary fleshing knife, an axle extending from the knife and disposed in said bearing, and coöperating means on the axle and frame to retain the former in the bearing.

7. In a fleshing machine, a supporting frame, one portion of the frame having a bearing, an axle receiving slot providing an entrance to the bearing, a socket surrounding the bearing, a rotary fleshing knife, an axle extending from the knife and disposed in said bearing, and an element disposable on said axle and engageable in said socket to retain the axle in said bearing.

10 8. In a fleshing machine, a supporting frame, one portion of the frame having a bearing, an axle receiving slot providing an entrance to the bearing, a socket surrounding the bearing, a rotary fleshing knife, an axle extending from the knife and disposed in said bearing, and a nut disposed on the axle and having an annular flange seated in said socket to retain the axle in the bearing.

15 9. In a fleshing machine, a supporting frame, a rotary fleshing knife journaled thereon, a carrying plate, an arcuate protector having a laterally extending attaching end adjustably secured to the carrying plate, and a hinge connection between the carrying plate and frame, said protector being adapted to partially encircle the knife or to be swung laterally to one side of the same.

20 30 35 10. In a fleshing machine, a supporting frame, a rotary fleshing knife journaled thereon, a carrying plate, an arcuate protector having a laterally extending attach-

ing end adjustably secured to the carrying plate, and a hinge connection between the carrying plate and frame, said protector being adapted to partially encircle the knife or to be swung laterally to one side of the same, and means for adjustably securing the carrying plate to the frame in position to partially encircle the knife with the protector.

11. In a fleshing machine, a supporting frame, one portion of the frame having a bearing, an axle receiving slot providing an entrance to the bearing, a rotary fleshing knife, an axle extending from the knife and disposed in said bearing, means for holding the axle in the bearing, an arcuate protector partially surrounding the fleshing knife when in normal position, said axle receiving slot of the bearing being positioned toward said protector, and means for hinging the protector to the frame to swing the same laterally of the fleshing knife to allow removal thereof from its bearing.

12. In a fleshing machine, a supporting frame, a rotary fleshing knife journaled thereon, a carrying plate pivoted to the frame, an arcuate protector secured to the carrying plate and partially encircling said knife when said carrying plate is swung to the limit of its movement in one direction, and means for locking said carrying plate in the last mentioned position.

In testimony that we claim the foregoing we have hereunto set our hands at Milwaukee, in the county of Milwaukee and State of Wisconsin.

JOHN O. SCHROEDTER.
JOHN KELLING.
